UNITED STATES PATENT OFFICE

HAROLD A. HICKS, OF DETROIT, MICHIGAN, ASSIGNOR TO FORD MOTOR COMPANY, OF DEARBORN, MICHIGAN, A CORPORATION OF DELAWARE

DESIGN FOR AN AIRPLANE

Application filed May 18, 1931. Serial No. 39,884. Term of patent 3½ years.

To all whom it may concern:

Be it known that I, HAROLD A. HICKS, a citizen of the United States, residing in the city of Detroit, county of Wayne, and State of Michigan, have invented a new, original, and ornamental Design for Airplane, of which the following is a specification, reference being had to the accompanying drawings, forming part thereof.

Figure 1 is a front elevation of an airplane, showing my new design.

Figure 2 is a side elevation of the airplane, shown in Figure 1, and

Figure 3 is a top view of the airplane, shown in Figures 1 and 2.

The lining is shown for the purpose of shading and does not designate color.

I claim:

The ornamental design for an airplane as shown and described.

HAROLD A. HICKS.
